UNITED STATES PATENT OFFICE.

GEORGE E. MERRILL, OF SALEM, MASSACHUSETTS.

WINDOW-VENTILATOR ATTACHMENT.

1,342,222.

Specification of Letters Patent.

Patented June 1, 1920.

Application filed October 25, 1918. Serial No. 259,672.

To all whom it may concern:

Be it known that I, GEORGE E. MERRILL, a citizen of the United States, residing at Salem, in the county of Essex and State of Massachusetts, have invented certain new and useful Improvements in Window-Ventilator Attachments, of which the following is a specification.

This invention relates to improvements in 10 ventilator attachments for windows and it is the principal object of the invention to provide a device capable of being arranged in a window in a manner to permit the ingress of sufficient fresh air to maintain the room 15 communicating therewith at a comfortable and healthful temperature and without alteration to the window or any parts thereof.

Another and equally important object of the invention is to provide a ventilator attachment which can be easily and quickly 20 adjusted to regulate the flow of fresh air therethrough into the room communicating therewith.

Other objects will be in part obvious and 25 in part pointed out hereinafter.

The improvements in the details and arrangement of parts will be apparent from an inspection of the accompanying drawings when considered in connection with the specific 30 description hereinafter contained and wherein a preferred embodiment of the invention is shown for the purpose of imparting a full understanding thereof.

In the drawings:

35 Figure 1 is a front elevation of the attachment as applied to a fragment of a window, Fig. 2 is an enlarged vertical transverse section therethrough, and

40 Fig. 3 is a perspective view of the attachment.

Having more particular reference to the drawings, in connection with which like reference characters will designate corresponding parts throughout the several views, 45 W indicates the window to which the attachment is applied in its entirety, said attachment being preferably engaged with a baseboard 1, which board is of a size to permit its arrangement in the window frame in a 50 manner as clearly shown in the Fig. 1 and is formed with an opening intermediate its ends, adjacent which the ventilator attachment is positioned.

The improved ventilator attachment in-

cludes a tapered housing 2 having an open 55 side wall and an open top, the open side wall thereof having apertured flanges 3 arranged thereabout to permit the securing of the attachment to the baseboard 1 as shown in the Figs. 1 and 2 by passing nails or other securing devices through the flanges into engagement with the board. Oppositely disposed ways 4 are formed adjacent the side portions of the open top of the casing 2 and align with a slot formed in one end wall 60 thereof whereby to permit the arranging of a slidable closure plate 5 therein, said plate carrying a knob, cleat or other suitable form of handle for an obvious purpose. In this connection, attention is directed to the 65 fact that the slidable closure plate 5 is arranged parallel to the adjacent face of the baseboard 1 and in consequence movement of the same to full or partly open positions or to full or partly closed positions can be 70 easily and quickly effected by a user.

In using the device, as hereinbefore stated, the baseboard 1 is arranged in the lower portion of the frame of the window W whereupon the lower marginal portion of 80 the adjacent sash is engaged with the upper edge of said baseboard, thus effectually closing the window. However, by moving the slidable closure plate 5 to the desired position, ingress of fresh air to the room 85 communicating with the device will be permitted to such extent as desired by the user.

The device by reason of its simple and compact construction can be applied to practically any form of window without alteration thereto and will be found to be advantageous and beneficial for use in connection with the rooms of a building, especially, sleeping compartments. By reason of the tapered formation of the casing 2, the beating of rain or snow into a room, the window of which is provided with the attachment, will be positively prevented, since, the same upon striking the inclined inner wall of the casing will quickly drain therefrom.

Manifestly, the construction shown is capable of considerable modification and such modification as is within the scope of my claims, I consider within the spirit of my invention.

I claim:

A ventilator attachment of the character described, comprising a base board adapted

100

105

to be engaged between the side portions of a window frame and having an opening formed in the intermediate portion, a casing secured to one side of said base adjacent the 5 opening and formed with an open side and an open top, the inner wall of said casing being inclined, and a closure plate slidably

engaged with the casing adjacent the open top and arranged parallel with the adjacent face of said base board.

10 In testimony whereof I affix my signature hereto.

GEORGE E. MERRILL.
